United States Patent Office.

WILLIAM F. TRAUTMAN, OF LLEWELLYN, PENNSYLVANIA.

Letters Patent No. 92,492, dated July 13, 1869.

IMPROVED EXTENSION-LADDER.

The Schedule referred to in these Letters Patent and making part of the same.

To all whom it may concern:

Be it known that I, WILLIAM F. TRAUTMAN, of Llewellyn, county of Schuylkill, and State of Pennsylvania, have invented a new and useful Improvement in "Extension-Ladders;" and I do hereby declare that the following is a full, clear, and exact description thereof, reference being had to the accompanying drawings, and to the letters of reference marked thereon, in which—

Figure 1 is a front elevation of my ladder extended, and ready for use.

Figure 2 is a side of same.

Figure 3 is a view of the ladder folded, or drawn together, so as to be transported.

Figure 4 is a side view, showing it arranged as a step-ladder, with platform attached.

Figure 5 is a top view of the jack used.

Figure 6 is a front view, showing the arrangement for shifting the ladder.

Figure 7 is a view of the catch and spring used in holding the ladder firmly against the wall.

To enable those skilled in the art to make and use my invention, I will now proceed to describe its construction and operation.

The ladder is made in three sections, A, B, and C, each of which is composed of two side-pieces, p , p^1 , p^2 , p^3 , p^4 , and p^5 .

Near the lower end of the section C, and working in bearings secured to the inner sides of the pieces p^4 and p^5 , is a windlass, W, provided with a pawl, P, and crank K.

Section B is placed on the back part of section C, and slides in guides G and G^1 , secured to the upper ends of the side-pieces p^4 and p^5 .

On the lower ends of the side-pieces p^2 and p^3 , of section B, are secured two guides, G^2 and G^3 , which pass around and slide on pieces p^4 and p^5 , of section C.

The side-pieces p and p^1 , of section A, are placed in front, and between the pieces p^2 and p^3 , of section B, and slide in guides G^4 , G^5 , G^6 , and G^7 , secured to the pieces p^2 and p^3 .

The upper ends of the sides p and p^1 have fitted over and secured to them sockets S and S' .

The upper ends of the said sockets are made so as to form open jaws, into which are placed and pivoted, by means of the pins N and N' , wheels E and E' .

On the inner side of the said wheels are placed catches T and T' , which are held in position by means of the pins N and N' passing through them.

On the lower edge and centre of the catches T and T' , a groove is formed, in which one end of the spring r touches, the opposite ends being secured to the inner sides of the sockets S and S' , as shown in fig. 7.

The catches T and T' are operated by means of the rope R, which is attached to the arm d.

Secured to the lower round of the section A, is a

rope, D, fig. 2, which passes over the upper round of the section B, and thence down and under the lower round of the same section, and thence over the upper round of the section C, and down the front of which, where it then passes to the windlass W, where it is attached, as shown by dotted lines, fig. 2.

When it is desired to form a step-ladder, the section A is withdrawn from the guides in section B, and the ends reversed, so that the projecting portions of the pins N and N' will fit into suitable openings made at the upper ends, and on the inner sides of the pieces p^2 and p^3 , as shown in fig. 6. The straps F and F' , which are pivoted, are then turned up and over the ends of the side-pieces p^2 and p^3 , thus holding the pins N and N' in place.

When it is desired to have a platform in connection with the step-ladder, or to erect a scaffold upon the extended ladder, (two or more ladders being required for this purpose,) I apply, as shown in fig. 4, to any of the rounds of the ladder, a jack, J.

The said jack is composed of a framing, and is attached to the rounds by means of hooks, which pass over the round, and is held in a horizontal position by means of braces.

In the centre of the section B, and secured to the inner sides of the pieces p^2 and p^3 , is a framing, I, which folds flat with the ladder when the sections are drawn together, and extends out when the ladder is extended, and serves as a king-post, in connection with the rope R', which is placed immediately back of it.

In order to hold the sections A, B, and C firmly apart when extended, I employ supporting-blocks H and H' .

The said blocks are attached to the lower round of each section by means of a strap, which encircles the round; and the opposite ends of the blocks are hollowed out, so as to fit over and rest on the upper rounds of the section immediately below it.

The operation is as follows:

The ladder, folded up as shown in fig. 3, is transported, by means of the wheels E and E' , to the locality desired to erect it. The ladder is then set up on an angle with the wheels resting against the wall. Crank K is then turned, and rotates the windlass W, and winds the rope D around it. This elevates the section B.

When the said section is at its height, and the ladder is required to be longer, the windlass W is again rotated, and the section A extended to the height desired. The centre part of the rope R has previously been hooked on to the hook L, on the end of the rope R'. The opposite end of the rope R' is now secured to the lowest round in section C. The framing I is then extended horizontally, and, pressing against the rope R', tightens it, so as to cause it (the rope R') to act as a brace, and stiffen the ladder.

When the rope R' is drawn taut, the sharp points on the catches T and T' will be projected against the wall, so as to prevent the ladder from working sideways.

The jack J, alluded to in the above description, can be used with doors, enclosing the space between the framing of same, so as to open, and allow a person to pass through, and then to close down, and form a platform.

I am aware that ladders have been constructed in several sections, sliding, one upon the other, for the purpose of extending the same, and do not broadly claim such device; but having thus fully described my invention,

What I claim therein as new, and desire to secure by Letters Patent, is—

1. The pivoted frame I and ropes R R', arranged and operating substantially as described, for the purpose of bracing the ladder when extended, as set forth.

2. The catches T and springs r, in combination with the upper section A and ropes R R', for the purpose of preventing end-motion of the ladder when placed in position, substantially as described.

3. The combination of the sockets S S', straps F F', pins N N', and sections A B, when arranged to operate substantially as described, and for the purpose of forming a step-ladder, in the manner set forth.

WILLIAM F. TRAUTMAN.
